UNITED STATES PATENT OFFICE

152,146

DESIGN FOR A THERMOSTAT COVER

Joseph G. Eldridge, Spring Valley, Ill., assignor to
Sears, Roebuck and Co., Chicago, Ill., a corporation of New York

Application March 13, 1947, Serial No. 137,588

Term of patent 7 years

(Cl. D52—7)

To all whom it may concern:

Be it known that I, Joseph G. Eldridge, a citizen of the United States of America and a resident of Spring Valley, in the county of Bureau and State of Illinois, have invented a new, original, and ornamental Design for a Thermostat Cover, of which the following is a specification, reference being had to the accompanying drawing, forming a part thereof.

Fig. 1 is a front elevational view of a thermostat cover, embodying my new design.

Fig. 2 is a side elevational view of the same.

Fig. 3 is a top plan view of the same.

Fig. 4 is a fragmentary sectional view, taken substantially along the line 4—4, Fig. 2.

The side not shown is substantially similar to the side shown in Fig. 2, and the bottom is substantially similar to the top shown in Fig. 3.

I claim:

The ornamental design for a thermostat cover, substantially as shown and described.

JOSEPH G. ELDREDGE.
